R. J. Roberts of New York, N.Y.

Letter's Patent, No. 2373. Dated July 24, 1866.

Design for a Trade Mark,

The schedule referred to in these letters Patent and making part of the same.

To all whom it may concern,

Be it known that I, R. J. Roberts, of the City County and State of New York, have invented a new and ornamental Design for a Trade Mark; and I do hereby declare that the following is a full, clear and exact description of the same.

Reference is to be had to the accompanying drawing.

In the central part of the ornamental Design is represented a human

Surrounding this figure are the words "Patent Parabola, these needles Warranted Excellent, R. J. Roberts"; the central figure and words are enclosed by the ornamental leaf work a, a, a, a, the whole to form a new and ornamental Design for a Trade Mark substantially as described.

It is claimed as new and elevitable security by Letter's Patent,

The within described Ornamental Design for a Trade Mark, substantially as shown in the drawing.

Witness,

W. J. Mc. Namara
